LOADED FILM CARTRIDGE

Harvey H. Dudley, Penfield, Robert I. Gresens, Rochester,
David E. Hansen, Fairport, Stephen H. Miller, Ironde-
quoit, and Robert C. Sutliff, Rochester, N.Y., assignors
to Eastman Kodak Company, Rochester, N.Y.

Filed Oct. 30, 1973, Ser. No. 411,125

Term of patent 14 years

Int. Cl. D16—05

U.S. Cl. D26—1 R

FIG. 1

FIG. 4

FIG. 2

FIG. 3

FIG. 5

FIG. 6

FIG. 7

FIG. 1 is a perspective view of a loaded film cartridge showing our new design;

FIG. 2 is a right side elevational view thereof;

FIG. 3 is a left side elevational view thereof;

FIG. 4 is a top plan view thereof;
FIG. 5 is a bottom plan view inverted with respect to the perspective view of FIG. 1;

FIG. 6 is a front elevational view thereof; and

FIG. 7 is a rear elevational view.

We claim:

The ornamental design for a loaded film cartridge, as shown.
